UNITED STATES PATENT OFFICE.

LEONARD ROY DICKERSON, OF CHICAGO, ILLINOIS.

TEMPORARY BINDER.

SPECIFICATION forming part of Letters Patent No. 793,356, dated June 27, 1905.

Application filed August 5, 1904. Serial No. 219,672.

To all whom it may concern:

Be it known that I, LEONARD ROY DICKERSON, a citizen of the United States, residing at Chicago, in the county of Cook and State of Illinois, have invented certain new and useful Improvements in Temporary Binders, of which the following is a specification.

One of the objects of this invention is the production of an improved locking device for temporary binders.

A further object of the invention is the general improvement of such binders.

The locking device herein shown and described is particularly applicable to temporary binders consisting of two clamping members or covers, one of which is slidable upon rods or posts carried by the other clamping member or cover.

In the accompanying drawings, Figure 1 is a transverse sectional view through a temporary binder embodying the features of my invention. Fig. 2 is a sectional view on dotted line 2 2 of Fig. 1. Fig. 3 is a section on dotted line 3 3 of Fig. 2. Fig. 4 is a fragmental sectional view illustrating a modified construction of the locking means.

In the drawings, 1 and 2 refer to the clamping side members, to which are flexibly attached the covers 3, said side members consisting of tubes having flat sides, rounded edges, and closed ends. To the side member 1 are rigidly secured binder-posts 4 of any suitable construction. As herein shown, these posts consist of short sections screwed together end to end. The fixed end 5 of the first section of each post is reduced in diameter and extends through the sides of the tubular side member 1 and through a metal block 6, lying in said side member, the outer end of said reduced portion being riveted down upon the side member to secure said post-section rigidly in place.

The binder-posts 4 extend through suitable openings 7 in the clamping side member 2. The mechanism for locking the side member 2 in position upon the binder-posts 4 is located within said side member and comprises a longitudinal shaft 8, provided at its ends with right and left hand screw-threads. Upon the screw-threads of said shaft are movably

mounted cam-blocks 9, each of which cam-blocks comprises a perforated ear 10 internally screw-threaded to engage the threads of the shaft 8, a wedging cam portion 11, and a rib 12, adapted to slide in contact with the inner edge wall of the tubular side member 2.

Near each of the binder-posts 4 a pin 13, riveted or otherwise suitably secured in the flat sides of the side member 2, serves as a pivot for a locking-dog 14. This locking-dog, which is pivoted at or near its longitudinal center, is notched in one end, as at 15, to engage the adjacent binder-post 4, its other end, 16, being wedging for engagement by the wedging portion 11 of the cam-block 9 on the adjacent end of the shaft 8. A leaf-spring 17, fixed at one end to the notched end of the dog 14, and at its other end bearing upon one of the inner edge walls of the side member 2, tends to hold the notched end of the dog out of engagement with the binder-post 4.

One end of the shaft 8 is squared, as at 18, to receive a socket-key (not shown) for rotating the shaft, an opening 19 being formed in the adjacent end wall of the side member 2 for the insertion of said key.

In use leaves or sheets suitably perforated or slitted are placed upon the binder-posts 4 and the side member 2 slid down upon said posts into contact with said sheets. The side member 2 is locked in this position by rotating the shaft 8 in the proper direction to cause the cam-blocks 9 to move toward each other. Such movement of the cam-blocks brings the wedging portions 11 of the blocks 8 into engagement with the wedging ends 16 of the locking-dogs 14, rocking said dogs upon their pivots 13 and bringing the notched ends of the dogs into frictional engagement with the binder-posts 4. When it is desired to move the side member 2 in order to make changes in the contents of the binder, the shaft 8 is rotated to move the cam-blocks 9 out of engagement with the locking-dogs 14, whereupon the leaf-springs 17 withdraw the notched ends of said dogs from engagement with the binder-posts 4. This withdrawal of the locking-dogs is especially advantageous in that the openings 7 in the side member 2 are thus entirely unobstructed when it is de-

sired to place the side member upon the binder-posts 4, said dogs lying at one side of said openings out of the way of said posts.

In Fig. 4 I have illustrated a slight modification of the locking mechanism, in which a notched locking-dog 20 is pivoted at one end and is moved into engagement with the binder-post 21 by means of a wedging-block 22, having a screw-thread engagement with the shaft 23. A leaf-spring 24 tends to move the dog 20 away from the binder-post 21, as in the construction first described. Rotating the shaft 23 in the proper direction moves the wedging-block 22 into engagement with the locking-dog 20, which latter is thereby rocked upon its pivot into frictional engagement with the binder-post. Rotating the shaft in the opposite direction withdraws the wedging-block from its engagement with the locking-dog and permits the spring 24 to raise the dog out of contact with the post 21.

It is apparent that various changes or modifications may be made in the construction herein described without departing from the spirit and scope of my invention, wherefore I desire to have it understood that I do not limit myself to the particular construction herein shown and described.

I claim as my invention—

1. In a temporary binder, in combination, a binder-post; a side member slidably mounted upon said post; a pivoted locking-dog adapted to engage said post; a slidably-mounted cam-block adapted to exert a wedging action for rocking said dog upon its pivot to move it into engagement with said post; and means operable from one end of said side member for sliding said cam-block.

2. In a temporary binder, in combination, a binder-post; a side member slidably mounted upon said post; a locking-dog adapted to engage said post; a screw; and a cam-block having a screw-thread engagement with said screw and adapted to move said dog into engagement with said post.

3. In a temporary binder, in combination, a binder-post; a side member slidably supported with relation to said post; a pivoted locking-dog having a wedging-surface and a notch adapted to receive said post; a wedging cam-block adapted to engage the wedging-surface of said dog to move said dog into engagement with said post; and means for moving said cam-block.

4. In a temporary binder, in combination, a binder-post; a tubular side member having an opening therein adapted to receive said post; a locking-dog pivoted within said side member and adapted to engage said post; a cam-block in said side member adapted to move said dog upon its pivot into engagement with said post; and means in said side member for moving said cam-block.

5. In a temporary binder, in combination, a binder-post; a side member slidably supported

with relation to said post; a locking-dog movably mounted with relation to said side member and adapted to engage said post; a screw; and means having a screw-thread connection with said screw for moving said dog into engagement with said post.

6. In a temporary binder, in combination, two binder-posts; a side member slidably supported with relation to said posts; locking-dogs movably mounted with relation to said side member and adapted to engage said posts; a shaft provided with right and left hand screw-threads; and means having a screw-thread connection with said shaft for moving said dogs into engagement with said posts.

7. In a temporary binder, in combination, two binder-posts; a tubular side member provided with openings for receiving said posts; two locking-dogs each pivotally mounted between its ends in said side member, said dogs each having a notch adapted to receive one of said posts; a shaft provided with right and left hand screw-threads at its opposite ends, said shaft being rotatably supported within said side member; and a cam-block having a screw-thread engagement with said shaft at each end thereof for pivotally moving said dogs.

8. In a temporary binder, in combination, a binder-post; a side member slidably mounted upon said post; a locking-dog adapted to engage said post; a screw; a cam-block having a screw-thread engagement with said screw and adapted to move said dog into engagement with said post; and a spring for moving said dog out of engagement with said post.

9. In a temporary binder, in combination, a binder-post; a side member slidably supported with relation to said post; a pivoted locking-dog having a wedging-surface and a notch adapted to receive said post; a wedging cam-block adapted to engage the wedging-surface of said dog to move said dog into engagement with said post; means for moving said cam-block; and a spring for moving said dog out of engagement with said post.

10. In a temporary binder, in combination, a binder-post; a tubular side member having an opening therein adapted to receive said post; a locking-dog pivoted within said side member and adapted to engage said post; a cam in said side member adapted to move said dog upon its pivot into engagement with said post; means for moving said cam; and a spring in said side member adapted to move said dog out of engagement with said post.

11. In a temporary binder, in combination, two binder-posts; a side member having openings therein adapted to receive said posts; locking-dogs pivotally mounted with relation to said side member and adapted to engage said posts; cam-blocks adapted to move said dogs into engagement with said posts; and a shaft having right and left hand screw-threads upon its opposite ends, with which screw-

threaded portions said cam-blocks have a screw-thread engagement.

12. A lock for loose-leaf binders consisting of upper and lower side members; binder-
5 posts arising from said lower side member; openings in said upper side member through which said posts pass; and means for locking said side members comprising a cam, a pivoted locking-dog having a reduced end portion that engages and is operated by said cam, a semicircular recess in the opposite end of

said dog that conforms in curvature with and engages one of said posts, and a bow-spring for retaining said dog normally out of engagement with its post, said spring engaging 15 said dog at one extremity and the edge of the side member at the other extremity at a point beyond said recess.

LEONARD ROY DICKERSON.
